UNITED STATES PATENT OFFICE

HARRY BERNARD, OF FORT SHERIDAN, ILLINOIS, ASSIGNOR OF ONE-HALF
TO THOMAS W. THORNE, OF CHICAGO, ILLINOIS.

PICCOLO OR OTHER MUSICAL INSTRUMENT.

No. 845,998.

Specification of Letters Patent.

Patented March 5, 1907.

Application filed July 22, 1905. Serial No. 270,868.

To all whom it may concern:

Be it known that I, HARRY BERNARD, a citizen of the United States, and a resident of Fort Sheridan, in the county of Lake and State of Illinois, have invented certain new and useful Improvements in Piccolo or other Musical Instruments, of which the following is a specification.

This invention relates more particularly to improvements in various kinds of musical instruments and in the method of fingering or operating such instruments. Its main objects are to simplify the operation of various instruments and also to simplify and improve the construction thereof.

Musical instruments of the lateral-vent variety, in which most of the gamut is sounded through side holes, are as constructed at the present time ordinarily provided with a large and bewildering number of keys to be manipulated to produce the various notes. This multiplicity of keys requires long practice and skilful fingering in order to properly play on such an instrument. For instance, in such a simple instrument as the piccolo it is required that six holes and six keys be under the control of the player. This of course requires double duty of some of the fingers and increases the difficulty for the player. The same objections are present in most of the instruments of this class. In fact, the principal change in these instruments for many years has been the addition of more keys, more holes, and more ways of making notes without providing simple or efficient controlling or operating devices.

According to this invention the scale is divided into semitones and a pair of such tones is apportioned to each finger, with an operative device common to all of the pairs and adapted to determine which one of any pair is to be sounded, this device being operated by means of a group-changing lever used in the regular operation of the instrument, as in running scales, &c. By means of this device and system of operation it is possible to greatly reduce the finger-work and still give a chromatic scale of two octaves, for instance, in a piccolo with six fingers on six keys. A result of this improvement is that no "fork-fingering" or side motion is ordinarily required, and the keys may be made large and of such a size that a player can readily use the instrument while wearing

gloves in cold weather. On account of the equal apportionment it is immaterial where a group of fingers is placed; so if the instrument is made a little longer to allow an extra key the scale can be commenced at that point, and thus an instrument is instantly in either C or B_b, for instance. Also by shifting the key mechanism up or down a semitone or half-tone difference is available. Thus the clarinet can be in C, B_b, and A. Instruments such as clarinets would require nine fingers to cover the gamut, while a piccolo, oboe, saxophone, or similar instruments would require but six fingers. By the fork-fingering which is always required on these instruments in the third register the remainder of the usual gamut is obtained.

This invention is intended to be applied to reed or other forms of musical instruments, as well as those above referred to, and my improved key mechanism may be applied in a large variety of ways. It provides for two octaves on any instrument by the simplest kind of up-and-down finger motion in rotation in a regular and simple order.

I have illustrated my invention in the accompanying drawings as applied to a piccolo in a number of different ways and also to a bassoon.

Figure 1 represents a plan view of a piccolo embodying this invention, parts being broken away for convenience in illustrating. Figs. 2 and 3 are details of the dogs on the selective device. Figs. 4 and 5 are details of the keys. Fig. 6 is a cross-section taken on the line 6 6 of Fig. 1. Fig. 7 is a sectional view taken on the line 7 7 of Fig. 1. Fig. 8 is an end view. Fig. 9 is a plan view of a modified form of construction. Fig. 10 is a similar view of the same device with the selective lever in change position and various parts omitted. Fig. 11 is a longitudinal sectional view of the device shown in Fig. 9 with parts omitted. Fig. 12 is a cross-sectional view on the line 12 12 of Fig. 10. Fig. 13 is a cross-sectional view on the line 13 13 of Fig. 9. Figs. 14 and 15 are detail views of the keys and key spring and stop. Fig. 16 is a plan view of a further modified form of construction. Fig. 17 is a similar view with the selective lever in changed position. Fig. 18 is a cross-sectional view on the line 18 18 of Fig. 16. Fig. 19 is an end view showing the inner-tube-rocking device. Fig. 20 is a side view of my im-

proved invention shown in modified form as applied to a bassoon. Fig. 21 is a front view of the same. Figs. 22 and 23 are details showing the valve mechanism. Figs. 24, 25, 5 and 26 are sectional views on the lines 24 24, 25 25, and 26 26, respectively, of Fig. 21.

In one embodiment or arrangement of my invention (shown in Figs. 1 to 8, inclusive) 10 10 represents a piccolo of any ordinary or 15 preferred form of construction provided with my improved key-operating device. 31 represents the selective lever or master-key which is connected or integral with the rod 32, which is carried in bearings 33 33 on the 20 side of the piccolo and is adapted to rotate therein. The lever 31 is held in normal raised position by means of the spring 34. A plurality of keys 35 are pivotally carried on the rod 32, and these keys are individually 25 held in raised position by means of springs 36. All of these keys, however, are controlled by the selective lever and may be simultaneously depressed by means of the dogs 37, which are adjustably secured to the 30 rod 32, these dogs being shown in detail in Figs. 2 and 3. A second series of keys 38 are also pivotally carried on the rod 32, these keys being held in normal raised position by means of stop-springs 39, as shown in Figs. 5 35 and 6, this spring being provided with heels or projections 39', which prevent the keys from being thrown out beyond normal position by the action of the springs. These keys are provided with overhanging projections 41, these projections extending over the 40 adjacent key 35 in each instance—that is, the arrangement is such that if one of the keys 38 is depressed it will also depress its companion key 35. Of course each of the 45 keys 35 and 38 is adapted to close a corresponding hole 42 in the side of the instrument, such holes representing, for instance, half-tones. The operation as thus applied to a piccolo or flute is as follows: With all of 50 the keys and the selective lever down the foot-note may be sounded. The lever 31 is then released, which opens the first key 35', which may be secured directly to the end of the rod 32, as shown in Fig. 1. Then by 55 alternately releasing the keys 38 and the lever 31 the succeeding higher notes or tones may be emitted. It will be noted that each time the lever 31 is held depressed while one of the keys 38 is released then after a note 60 has been sounded with the key 38 up the next half-tone is sounded, when the lever 31 is released, allowing the mate key 35 to raise. It will thus be seen that by means of my invention substantially every other key is controlled by means of the group-changing lever 31, which has for convenience been termed the "selective" lever.

The same results have been accomplished by means of the modified form of construction shown in Figs. 9 to 15, inclusive. In ac-

cordance with this construction the instrument 43 is provided with a plurality of side holes 44, the alternate ones of which may be respectively opened or closed by means of a slide 45, which is arranged in the guideway 70 46, as shown in Figs. 9 to 11, said guideway being provided with holes corresponding with those in the instrument. The arrangement is such that when the slide 45 is in its normal position (shown in Fig. 11) each alternate hole in the instrument will be opened and the intermediate holes closed; but when the slide is shifted the holes which were previously opened will be closed and the other holes opened. The slide is held in normal 80 position by means of a spring 47, which is secured to one end thereof and is fastened at the opposite end to body of the instrument, as by means of a brace 48. The slide is moved by means of the lever 49, which is 85 pivoted at 50 to the instrument and is loosely attached at 51 to the slide, such attachment allowing for the free swinging of the lever and movement of the slide. The keys 52 are pivoted on a rod 53 and are held in normally 90 raised position by means of springs 54, which coact with stops 55, as shown in Figs. 14 and 15, the latter preventing the keys from swinging out of operative position. Each of the keys 52 takes over and controls two of 95 the openings 44, such openings representing, for instance, half-tones. The operation in running the chromatic scale is similar to that above described. For instance, with the lever 49 depressed and the keys down, releasing 100 a key will allow the corresponding tone to be emitted. Then releasing the lever while the key is still up will allow the higher half-tone to be emitted, and so on through the scale.

Substantially the same result may be accomplished by the modified form of apparatus shown in Figs. 16 to 19, inclusive. In this case the instrument 56 is provided with holes 57, such holes being shown with two openings for each tone, this arrangement being advantageous, as it allows a larger opening without cutting away too much of the sides of the instrument and lessens the necessary movement of the inner tube. The holes are arranged in pairs, as above described, 105 corresponding with tones and half-tones, and the alternate holes (as represented by the double openings) may be opened and closed by means of the oscillating inner tube 58, which is provided with offset holes 59 for 110 this purpose. The arrangement is such that when the tube is in normal position, as shown in Fig. 16, the alternate holes, beginning with the one nearest to the outer end of the instrument, are open and the others closed. 115 When the tube 58 is turned, it brings the second set of holes therein to register with the corresponding holes in the instrument and closes the first-mentioned holes. This tube 120 is shifted or turned by means of the lever 60, 125 130

which is connected with the pivot-rod 61, having a finger 62' on the opposite end thereof, which enters a slot in the tube. This lever may be held in normal position by means 5 of a spring or the like. Pivots arranged on the rod 61 are a number of keys 62, each of said keys being held in raised position by springs, as above described, and each of said keys taking over or controlling two holes or 10 outlets corresponding with two tones in the side of the instrument. The operation is substantially the same as for the last-described modification, the tube being shifted to open and close the different holes in place 15 of the slide above described.

A different embodiment of the main inventive idea is shown in Figs. 20 to 26, inclusive, in which my invention is shown as applied to a bassoon or similar instrument. In 20 this case half-tones are provided by having two tubes of unequal length. 63 represents the shorter or straight tube, and 64 the longer tube, which may be, for instance, a half-tone lower than the first tube, the elongation occurring between the inlet-aperture and the first set of side holes 65. The mouthpiece or inlet-pipe 66 is connected with the tubes 63 and 64 by means of three-way valve 67, which is fully illustrated in Figs. 20, 22, and 25 30. This valve is operated by means of a lever 68, which corresponds with the selective lever above described. The valve is held in normal position, in which the openings lead to the pipe 64, by means of the spring 69, the lever 68 striking against a pin-stop 70 on the valve-casing. Each of the keys 71 is adapted 35 to cover two holes, one in each pipe, respectively, said holes corresponding with different tones—for instance, semitones. The 40 keys are held in normal open position by means of springs, such as shown in Fig. 15, on the levers 72. These levers are pivotally connected in suitable bearings on the sides of the tubes and extend up to convenient 45 points near the mouthpiece, where they terminate with suitable disks for engagement with the fingers. This embodiment of the invention produces substantially the same results as shown heretofore—that is, with all 50 of the keys and lever 68 down a tone may be produced through one of the side orifices by raising any one of the keys. Then with the key still raised, releasing the lever 68 will direct the vibrations through the longer tube 55 and the corresponding half-tone will be produced. The whole scale may be run in a similar manner.

From these examples it is evident that my invention may be applied in a large variety 60 of ways to various instruments and is readily adapted to minor modifications. For this reason and from the fact that the general construction of such musical instruments is

familiar to those versed in the art, I have not entered into the minute details of construction. 65

It is my object in this application to cover broadly the essential inventive feature or system which consists in combining with a musical instrument any suitable means 70 whereby the fingering is simplified in the manner herein suggested and a large number of tones placed under the control of a selective device or master-key.

Having thus described my invention, what 75 I claim, and desire to secure by Letters Patent, is—

1. A piccolo provided with lateral holes arranged longitudinally of the piccolo, and a perforated slide having holes therein so 80 spaced that in one position a predetermined number of holes are in register with a corresponding number of holes in the instrument and in another position the remaining holes of the slide are in register with the remaining 85 holes of the instrument, and means for rapidly operating said slide in the regular operation of the instrument.

2. A musical instrument provided with lateral tone-regulating holes arranged in one 90 line, and means comprising a perforated slide having holes to register, at times, with the alternate holes of the instrument while the remaining holes are covered, means for operating said slide, and a plurality of keys, each 95 key being adapted to cover a plurality of adjacent holes of the instrument.

3. A musical instrument provided with lateral holes, and a perforated slide with as many holes as in said instrument, but so 100 spaced that in one position half of the holes are in register alternately and in another position the other half, a spring for holding said slide in normal position, a lever for reciprocating said slide to its adjusted position, and 105 a plurality of pivoted keys, each key being adapted to cover two holes of the instrument, and means for holding each key in normally raised position.

4. A musical instrument provided with a 110 plurality of tone-regulating holes for notes of different pitch, and means for simultaneously opening or closing sets of alternate holes in the regular operation of the instrument, and keys each adapted to cover two or more of 115 the holes of the instrument.

5. A musical instrument provided with a plurality of holes for tones of different pitch, and means for simultaneously opening or closing sets of alternate holes, and keys, each 120 key being adapted to cover two or more of the holes in the instrument.

HARRY BERNARD.
